UNITED STATES PATENT OFFICE.

ALBERT GEE, OF ELKINS PARK, PENNSYLVANIA.

DESIGN FOR HOSIERY.

Application filed March 15, 1929. Serial No. 30,479. Term of patent 7 years.

To all whom it may concern:

Be it known that I, ALBERT GEE, a citizen of the United States, residing at Elkins Park, in the county of Montgomery and State of Pennsylvania, have invented a new, original, and ornamental Design for Hosiery, of which the following is a specification, reference being had to the accompanying drawing, forming a part thereof.

I claim:

The ornamental design for hosiery, as shown.

ALBERT GEE.
